UNITED STATES PATENT OFFICE

ALBERT L. MARTIN, OF SHAKER HEIGHTS, OHIO, ASSIGNOR TO THE VLCHEK TOOL COMPANY, OF CLEVELAND, OHIO, A CORPORATION OF OHIO

MERCHANTISE DISPLAY BOX

Application filed March 5, 1929. Serial No. 344,251.

My invention relates to display boxes for articles of merchandise such as tools and the like, and the principal object of my invention is to provide a new and improved device of this type. In the drawings accompanying this specification and forming a part of this application I have shown, for purposes of illustration, one form which my invention may assume and in these drawings:

10 Figure 1 is a perspective view of this illustrative embodiment of my invention showing the cover in closed position,

15 Figure 2 is a fragmentary section showing the cover in contact with the box as shown in Figure 1,

Figure 3 is a perspective view showing the cover in open position,

20 Figure 4 is a fragmentary section showing the cover in open position as shown in Figure 3,

Figure 5 is a side elevation of Figure 2 showing the display holder in place, while

25 Figure 6 is a top plan view with the cover removed.

I show my invention embodied in a display box 11 comprising a base 13 from which rise four side walls 14 suitably secured to the base 13 and each having a scroll portion 18 substantially near the top, two of the opposing side walls 14 having cut away portions 20 along their top edges for affording access to the interior of the edge of a cover. Each of the four side walls 14 are provided with two inwardly projecting lips 15 positioned substantially near the top edges of the four walls 14 and immediately below the scroll portions 18 and formed by cutting away small arch shaped portions of the side walls 14 and then bending such portions inwardly. The portions of the side walls 14 immediately above said cut away portions are forced inwardly forming small projections 19, while mounted in the bottom section 13 of the display box 11 are a plurality of upwardly projecting pegs 16 extending from the inner surface of the bottom section 13 upwardly substantially the height of the lips 15 from the bottom section 13, the pegs 16 herein shown being nails driven through the bottom section 15 from the outside thereof and arranged in tiers suit-

ably positioned and spaced to support articles of merchandise herein shown as wrenches 17 of varying sizes.

A cover 12 fitting within the top edges of the four walls 14 is provided with a skirt section 21 formed integrally therewith and has outwardly extending flanges 22 extending completely therearound, the outer peripheries of the flanges 22 being adapted to rest upon the projections 19 in the side walls 14 when the cover 12 is inserted with the skirt section 21 extending toward the bottom section 13 as shown in Figure 1. The cover 12 is also adapted to be inserted within the four walls 14 with the skirt section 21 extending away from the bottom section 13 and when the cover 12 is in such position the outer peripheries of the cover 12 rest upon the lips 15 on the side walls 14 as shown in Figure 3.

The inner side of the cover 12 is provided with lithographic representations 24 of the various size wrenches contained in the display box 11 and further is provided with straps 23 suitably secured thereon and adapted to securely grasp and hold thereon an article of merchandise herein shown as a wrench 17.

A quickly attachable and detachable display holder 25 of any suitable type provides 80 means for supporting the display box 11 at a predetermined angle, as shown in Figure 5.

In actual use I find it convenient to place a set of similar wrenches horizontally in the display box 11 between two corresponding sets of pegs 16, the relative positions of the pegs 16 being varied according to the different sizes of wrenches to be supported by the display box 11. In the usual practice the display box 11 is filled with wrenches and the display holder is loosely mounted on top of the wrenches immediately below the cover 12 and one wrench is usually mounted on the inner side of the cover 12 by the strap 23. The cover is placed within the top edges of the four side walls 14 with the outer peripheries of the flanges 22 resting on and supported by the small projections 19. The display box 11 containing the wrenches then is ready to be shipped for display and use.

A merchant receiving a display box 11 carrying the wrenches 17 as above set forth first removes the cover 12 and holder 25 and then turns the cover over and inserts it within the top edges of the four side walls 14 with the skirt section 21 extending upwardly, the cover 12 being held and supported in this position by the lips 15 engaging and supporting the outer peripheries of the cover 12. The display holder 25 then is brought into position to support the display box 11. On account of the lithographic representations on the cover of the various sizes of wrenches contained within the display box 11 it is necessary to have but one wrench on display.

The cover 12 is easily removed to obtain a wrench from within the box for display and sale, or to replace a wrench, and as the stock of any size becomes depleted it can be renewed by inserting additional wrenches, as from a refill package or shipment.

From the above description it will be obvious to those skilled in the art that I have provided a new and improved display box of the type described. At the same time it also will be obvious to those skilled in the art that the embodiment of my invention herein shown and described embodies advantages and uses other than those particularly pointed out or suggested herein, and also that this particular embodiment of my invention disclosed herein may be variously changed, modified, or used without departing from the spirit of my invention or sacrificing the advantages therein, wherefore it will be understood that the disclosure herein is illustrative only, and that my invention is not limited thereto.

I claim:

1. A display box, as for containing and exhibiting articles of merchandise such as tools and the like, comprising: a box for containing a supply of said articles and having connected bottom and side walls; a cover readily adaptable to be inserted and held within the side walls of said box with either surface of said cover outwardly disposed and substantially parallel with reference to said bottom wall, to provide a shipping top for said box when said cover is positioned therein with one side out and a display top when it is positioned therein with its other side out; and means for supporting on said other side of said cover a sample of said articles contained in said box.

2. A display box, as for containing and exhibiting articles of merchandise such as tools and the like, comprising: a box for containing a supply of said articles and having connected bottom and side walls; means mounted in said box for securely supporting said articles therein; a detachable cover readily adaptable to be inserted and held within the side walls of said box with either surface of said cover outwardly disposed with refer-

ence to said bottom wall, to provide a shipping top for said box when said cover is positioned therein with one side out and a display top when it is positioned with its other side out; and means for supporting on said other side of said cover a sample of said articles contained in said box.

3. A display box, as for containing and exhibiting articles of merchandise such as tools and the like, comprising: a box for containing a supply of said articles; a cover readily adaptable to be inserted and held within the sides of said box with either surface of said cover out, to provide a shipping top for said box when said cover is positioned therein with one side out and a display top when it is positioned therein with its other side out; means for supporting on said other side of said cover a sample of said articles contained in said box; and representations of the various articles contained in said box mounted on said other side of said cover.

4. A display box, as for containing and exhibiting articles of merchandise such as tools and the like, comprising: a box for containing a supply of said articles, having side walls provided with interior projections disposed inwardly of the edges of said side walls; a cover readily adaptable to be inserted within the sides of said box and supported by said projections with either surface of said cover out, to provide a shipping top for said box when said cover is positioned therein with one side out, and a display top when it is positioned therein with its other side out; and means for supporting on said other side of said cover a sample of said articles contained in said box.

5. A display box, as for containing and exhibiting articles of merchandise such as tools and the like, comprising: a box for containing a supply of said articles, having side walls provided with interior projections disposed at different levels; a cover readily adaptable to be inserted within the sides of said box with either surface of said cover out, and supported by said projections at one level to provide a shipping top for said box when said cover is positioned therein with one side out and supported by said projections at a different level to provide a display top when it is positioned therein with its other side out; and means for supporting on said other side of said cover a sample of said articles contained in said box.

In testimony whereof I hereunto affix my signature.

ALBERT L. MARTIN.
